CLAIM

The ornamental design for a grip portion of hand held scanning tool, as shown and described.

DESCRIPTION

FIG. 1 is a perspective view of a grip portion of hand held scanning tool showing my new design on an enlarged scale; FIG. 2 is a front view thereof; FIG. 3 is a bottom view thereof; FIG. 4 is a right side view thereof; FIG. 5 is a left side view thereof; and, FIG. 6 is a rear view thereof.

The broken lines shown in FIGS. 1-6 are environmental only and form no part of the claimed design.
